UNITED STATES PATENT OFFICE

HENRY C. EGERTON, OF PASSAIC, NEW JERSEY, ASSIGNOR TO WESTERN ELECTRIC COMPANY, INCOPORATED, OF NEW YORK, N. Y., A CORPORATION OF NEW YORK.

MACHINE AND METHOD FOR WINDING ELECTRICAL COILS.

Application filed December 29, 1920. Serial No. 433,756.

To all whom it may concern:

Be it known that I, HENRY C. EGERTON, a citizen of the United States, residing at Passaic, in the county of Passaic, State of

6 New Jersey, have invented certain new and useful Improvements in Machines and Methods for Winding Electrical Coils, of which the following is a full, clear, concise, and exact description.

10 This invention relates to machines and methods for winding electrical coils.

In the construction of induction coils it is well known that a considerable saving can be obtained if the iron core is allowed to extend out past the ends of the coil since, of course, fewer turns of wire are required than when the windings cover the entire core. It has been found that a highly efficient coil is produced and that a further 15 saving is effected if the wire is tapered so that there are fewer turns at each end of the coil, the number gradually increasing toward the center; or in other words, so that there are a greater number of turns on the 20 inside layer, this number decreasing toward the outer layer.

It is one object of the invention to provide apparatus for winding a coil of this type, in which a cotton binding thread and 25 the wire are wound simultaneously, the number of turns per layer being subjected to automatic control.

In the preferred form of the invention, there is provided a main shaft carrying 30 an arbor for winding the coil and a cam belted to the shaft to control the feed of cotton serving, the feed of the wire being controlled by a lathe screw. The proper number of turns per layer is determined by 35 employing a drum which will be stepped forward one position each time the feed reverses. The feed member carries a contact device which makes contact at the end of each travel with a contact plug in the drum, 40 and as this contact is made, a magnet is operated which reverses the feed. By proper placing of contact plugs in the drum, the number of turns per layer may be controlled. The wire, as has been noted, is tapered on the coil, but the cotton is allowed 45 to feed constantly across the coil and is allowed to build up at each end to form a spool head intended to strengthen the mechanical structure of the coil.

50 The invention will be better understood

from a consideration of the following description taken in connection with the accompanying drawing and the appended claims.

Referring to the drawing in the preferred 60 form of the invention, a main shaft 1, adapted to be driven by any suitable means, such as a motor 2, is provided with an arbor or spindle 3 for winding the coil. A cam 4, adapted to control the feed of cotton from the spool 5 is belted to the shaft 1 by means of the wheel 6 and belt 7. A bar 8, pivotally mounted on the supporting plate 9, mounts a roller 10 which is held in engagement in the slot 11 of the cam 4. An arm 12 is provided, one end of which is pivoted on the bar 8, the opposite end containing a bolt 13 which is adjustably mounted in the vertical slot 14 of the guide plate 15. The fibrous insulating material passes from the spool 5 over the guiding roller 16, and is served through the eyelet 17 of the guide plate 15 upon the arbor 3. It will be seen that by adjusting the bolt 13 in the slot 14 70 the distance over which the cotton is served 75 may be adjusted in accordance with the length of the coil required.

The feed of the wire from the spool 18 is controlled by a lathe screw feed consisting of the threaded shaft 19 and the feed 80 member 20, the inner tubular portion of which is threaded to engage similar threads of the shaft. The guide member 21 is adapted to hold the feed member 20 from rotating with the shaft 19. On the main shaft 1 are 85 mounted the pinions or cog-wheels 22 and 23, the teeth of the pinion 23 engaging the teeth of an idler pinion 24 causing the said idler pinion to rotate in a direction opposite to the rotation of the shaft 1, as indicated 90 by the arrows in the drawing. The shaft 19 is provided with a pinion or wheel 25, and the said shaft is slidably mounted so that the wheel 25 may engage either the wheel 22 of the main shaft 1, or the wheel 100 24. It will thus be seen that when the wheel 25 is in operable engagement with the wheel 22, the shaft 19 will rotate in a direction opposite to the rotation of the shaft 1, and the feed member 20 will move from left to right 105 along the threaded portion of the shaft 19. When, however, the pinion 25 is in operable engagement with the idler pinion 24, the shaft 19 will rotate in the same direction as the shaft 1, and the feed member 20 will 110

move from right to left along the shaft 19. The wire from the spool 18 passes over the guide roller 26 and is served through the eyelet 27 of the feed member 20 upon whatever portion of the arbor 3 that the moving feed member is passing at the moment. The feed member 20 carries a pair of contacts 28 and 29, one of which makes at the end of each travel with a protruding contact of the drum 30. The spiral converging contact plugs, those on one end of the drum 30 being indicated by the numeral 31, and those on the opposite end by the numeral 32, are so spaced on the drum 30 as to indicate the proper number of turns of wire per layer in the coil under construction. The reversing mechanism is operated by the electromagnets 33 and 34, the pivoted armature 35 of which is forked at one end to engage the circular slot 36 of the shaft 19. The contacts 28 and 29, as well as the contact plugs 31 and 32, are connected in circuit with the electromagnets 33 and 34 in such a way that when either contact 28 or 29 makes, at the end of each travel, with either contacts 31 or 32, one of the said electromagnets will be energized to attract the armature 35. As this is done, the position of the pinion 25 on the shaft 19 will be shifted, and the feed of wire reversed. An electromagnet 37 is provided to control the rotation of the drum 30, the end of the armature 38 being adapted to engage the teeth of ratchet wheel 39 of the drum 30. The electromagnet 37 is so connected that every time the above-mentioned contacts make to reverse the feed, current from battery 40, which operates windings 33 and 34, also energizes the windings of electromagnet 37 to attract armature 38, which action steps around the drum 30 one position.

With the arrangement here shown and described, in which the feed of the wire is constant, the change in the different layers is accomplished by timing the reverse. Thus the layer of wire nearest the core may contain a great many turns; each succeeding layer of wire, however, will contain fewer turns of wire, the number of turns being controlled by the predetermined position of the plug contacts 31 and 32 of the drum 30.

No attempt has been made to change the feed of the cotton, because if this is allowed to feed constantly across the coil, the cotton will build up at each end and form a sort of spool head which will tend to strengthen the mechanical construction of the coil.

A disk member might, of course, be substituted for the drum 30, and certain other changes in the construction of the device as herein described may obviously be made. It is therefore not intended to limit the invention to the construction shown except within the scope of the appended claims,

What is claimed is:

1. In a coil winding machine, a rotatable arbor, an adjustably mounted rotatable shaft, a feed member disposed on said shaft and adapted to act as a guide for the wire, a drum, a plurality of contacts mounted on said drum and adapted to control the serving of the wire upon said arbor, an electromagnet, an armature for said electromagnet, and means associated with said feed member adapted to contact with said drum contacts to cause said armature to step around said drum. 70

2. In a coil winding machine, a rotatable arbor, an adjustably mounted rotatable shaft, a feed member disposed on said shaft and adapted to act as a guide for the wire, a contact mounted on said feed member, a rotatable drum member, a plurality of contacts mounted on said drum member and adapted for engagement with said feed contact, and means whereby the engagement of said feed contact with any of said drum contacts will serve to adjust the position of said shaft. 80

3. In a coil winding machine, a drum, a plurality of contacts mounted on said drum, a rotatable arbor, a feed member adapted to act as a guide for serving wire upon said arbor, reversing mechanism for said feed member, a contact carried by said feed member, and means for operating said reversing mechanism upon engagement of said feed and drum contacts. 85

4. The method of producing electrical coils which consists in simultaneously winding conducting material and insulating material in superimposed layers, the conducting material being wound so that there are a greater number of turns on the inside layer, this number decreasing toward the outer layer, and the insulating material being wound continuously across the coil, each succeeding layer containing substantially the same number of turns as the layer below it. 100

5. The method of producing electrical coils which consists in simultaneously interweaving conducting material and insulating material in superimposed layers, the conducting material being wound so that there are a greater number of turns on the inside layer, this number decreasing toward the outer layer, and the insulating material being wound continuously across the coil each succeeding layer containing substantially the same number of turns as the layer below it. 115

6. A coil winding machine comprising a rotatable shaft, an arbor mounted on said shaft, a second rotatable shaft slidably mounted so that it may rotate with the first shaft or in an opposite direction thereto according to its position, a feed member mounted on said second shaft and adapted 120

- to travel thereon to act as a guide for serving conducting material upon said arbor, a contact carried by said feed member, a rotatable drum member, a plurality of contact plugs mounted on said drum member and adapted for engagement with said feed contact, an electromagnet connected in circuit with said feed contact, and said contact plugs, an armature for said electromagnet, one end of said armature being in engagement with said second shaft, whereby when the circuit including said contacts is closed, the said armature will be attracted to shift the position of said second shaft to cause the shaft to rotate in the opposite direction.
7. In a coil winding machine, an arbor, means for rotating said arbor, means for serving fibrous insulating material upon said arbor, a lathe screw feed comprising a rotatable shaft and a feed member for a wire guide adapted to travel upon said shaft upon rotation of said shaft, a reversing mechanism to control the direction of travel of said feed member, a reversing magnet to control said reversing mechanism, a rotatable drum member, a plurality of spirally
- converging contacts mounted on said drum member, a contact carried by the said feed member and adapted to contact with said drum contacts to operate said reversing magnet, and a stepping magnet adapted to change the position of said rotatable drum upon the operation of said reversing magnet.
8. A coil winding machine comprising a rotatable arbor, means for serving insulating material and wire simultaneously upon said arbor, means for obtaining a uniform number of turns of insulating material on each layer, and means whereby the number of turns of wire may be automatically decreased with each succeeding layer.
9. A coil winding machine comprising a rotatable arbor, means for interweaving insulating material and wire on said arbor, means for obtaining a uniform number of turns of insulating material on each layer, and means whereby the number of turns of wire may be automatically decreased with each succeeding layer.
- In witness whereof, I hereunto subscribe my name this 24th day of December A. D., 1920.

HENRY C. EGERTON.
